UNITED STATES PATENT OFFICE.

WILLIAM ALSIP, OF MOMENCE, ASSIGNOR TO THE TIFFANY PRESSED BRICK COMPANY, OF CHICAGO, ILLINOIS.

BRICK-KILN.

SPECIFICATION forming part of Letters Patent No. 340,186, dated April 20, 1886.

Application filed January 18, 1886. Serial No. 188,949. (No model.)

To all whom it may concern:

Be it known that I, WILLIAM ALSIP, a citizen of the United States, residing at Momence, in the county of Kankakee, State of Illinois, 5 have invented certain new and useful Improvements in Brick-Kilns, of which the following is a specification, reference being had therein to the accompanying drawings.

This invention relates to brick-kilns in 10 which the products of combustion enter either at the top or bottom of the kiln, and in which alternate up and down drafts are secured from the same fires.

The object of the invention is to provide a 15 brick-kiln of this character which will afford an equal distribution of the heat from the same fires in both the up and the down drafts.

In the accompanying drawings, Figure I is a side elevation of this improved brick-kiln. 20 Fig. II is a transverse section thereof on line ii ii of Fig. IV. Fig. III is a longitudinal section on line iii iii of Fig. II. Fig. IV is a horizontal section on line iv iv of Fig. III.

Corresponding parts in the different figures 25 are designated by the same numbers.

The kiln 1, which is preferably square or 30 rectangular in shape, is strengthened by trussed braces 2, which are connected over the arched top 3 thereof by means of tie-rods 4. Furnaces 5 are arranged, preferably, along 35 opposite sides of the kiln, each furnace comprising a fire-box, 6, and an ash-pit, 7. The kiln is provided between the furnaces with doorways 8, and immediately above the furnaces with damper-openings 9, and immediately 40 between said damper-openings 9 with similar damper-openings, 10. The furnaces 5 are elevated relatively to the kiln, and fire-holes 11 in the walls of the latter establish

communication between the fire-boxes 6 and a series of broad vertical flues, 12, arranged 45 along the side of the kiln opposite the furnaces, said fire-holes being at points about midway between the upper and lower ends of said flues, which latter extend upward and open at their upper ends into the kiln near the roof thereof, and also extend downward below the floor of the kiln. These flues 12 are provided above the fire-holes 11 with dampers 13, and 50 below said fire-holes with dampers 14, whereby they may be changed from ascending to de-

scending flues, or the converse. They are also provided near the floor of the kiln above the lower damper, 14, with perforations 15. Longitudinal distributing-flues 17 are located 55 below the floor on opposite sides of the kiln near the side walls thereof, and communicate with the vertical flues 12 at the lower ends of the latter through openings 16. These longitudinal distributing-flues also communicate 60 by openings along their tops with a series of transverse distributing flues or channels, 18, immediately beneath the floor of the kiln. The floor 19 of the kiln is closed or solid for a distance of about three feet (more or less) 65 from each of the side walls, and the central portion thereof is provided with openings or holes 20, to establish communication between the interior of the kiln and the transverse flues 18. A series of smaller vertical flues, 70 21, are arranged along the sides of the kiln between the flues 12, opening at their upper ends near the top of the kiln. These flues 21 serve solely as descending exit-flues, and extend to points below the lower end of the flues 75 12, and communicate at their lower ends through openings 22 with horizontal exit-flues 23, which extend longitudinally of the kiln beneath the longitudinal distributing-flues 17. The flues 21 are provided with dampers 26, 80 whereby they may be closed. The longitudinal side exit-flues, 23, communicate with the smoke-stack. A horizontal central exit-flue, 24, extends longitudinally of the kiln beneath the floor thereof and below the transverse flues 18. This flue also connects with the smoke-stack, and is provided along its 85 top with openings into the transverse flues or channels 18, and at its outer end with a damper, 25, whereby it may be closed.

The operation is as follows: The bricks to be burned are stacked in the kiln in any approved manner and the fire started in the furnaces along the sides thereof. If it be desired to first subject the bricks to a downdraft of 95 the heat and fire-gases, the lower dampers, 14, of the vertical flues 12 are closed, the upper dampers, 13, of said flues opened, and the damper 25 of the central exit-flue, 24, opened. The direction of the heat will then be, as indicated by the full-line arrows, through the fire-holes 11 into the vertical flues 12, and up-

ward through the upper portion of said flues into the interior of the kiln near the top thereof. The heat and gases then descend within the kiln toward the center thereof between the 5 bricks stacked therein, and pass through the openings 20 in the floor into the transverse channels 18, thence into the central exit-flue, 24, whereby they are conducted to the smoke-stack. A small portion of the heat 10 and fire-gases will descend a short distance in the flues 12 and pass through the perforations 15 into the kiln, coming in contact with the bricks stacked near the sides of the kiln on the solid portions of the floor. After the 15 bricks have been subjected for a given period of time to the downdraft the current is reversed, and they are subjected for another period of time to an upward current. This reversal of the current is effected by closing 20 the upper dampers, 13, in the flues 12, opening the lower dampers, 14, in said flues, opening the dampers 26 in the vertical flues 21, and closing the damper 25 in the central exit-flue, 24. The course of the heat and products of 25 combustion from the furnaces to the smoke-stack, as indicated by the dotted arrows, will then be as follows: from the furnaces through the fire-holes 11 into the vertical flues 12, downward through the lower parts of said flues to the 30 lower ends thereof, thence through the openings 16 into the longitudinal distributing-flues 17, thence through the tops of said flues into the transverse distributing-flues 18, thence along said flues toward the center of the kiln, thence 35 through the openings 20 in the floor into the kiln, thence upward through the kiln between the bricks stacked therein to near the top thereof, thence downward through the descending flues 21 to the lower ends of said 40 flues, thence through the openings 22 into the horizontal side exit-flues, 23, whereby they are conducted to the smoke-stack. A portion of the gases will pass into the kiln during the 45 updraft current through the perforations 15, so as to burn the bricks on the solid portion of the floor in the same manner as during the downward current of the main portion of the gases. The bricks may first be subjected to the upward current, and subsequently to the 50 downward current, if preferred. The elevation of the fire-boxes and the location of the fire-holes at the points about midway between the upper and lower ends of the vertical flues 12 secure an even distribution of the heat, 55 whether a down-and-up or an up-and-down draft be employed; and the construction of the floor with solid side portions serves to direct the heat toward the center of the stack, and, together with the separate supply-openings 60 15 for the bricks on the solid parts thereof, tend further to equalize the temperature of the kiln and secure an even burning of the bricks throughout the entire stack.

A series of separate kilns may be located in 65 one structure and divided by transverse partition-walls.

This improved kiln is of especial advan-

tage in the burning of bricks formed of dry clay, or clay which is somewhat refractory in character.

I claim as my invention—

1. The combination, substantially as set forth, with a brick-kiln, of a vertical flue in communication with said kiln at or near the top and at the bottom thereof, and a fire-box in communication with said flue at a point about midway between the upper and lower ends thereof, said flue being provided with dampers for reversing the current above and below the opening communicating with the fire-box.

2. The combination, substantially as set forth, with a brick-kiln, of a vertical flue opening into the kiln near the top thereof and extending below the bottom thereof, a furnace having an elevated fire-box communicating with said flue about midway between its upper and lower ends, said vertical flue being provided with dampers above and below the opening communicating with the fire-box, and flues connecting the lower end of said vertical flue with the bottom of the kiln through openings in the floor thereof.

3. The combination, substantially as set forth, with a brick-kiln, of a vertical flue opening at its upper end into the kiln near the top thereof and extending below the bottom thereof, an elevated fire-box in communication with said flue at a point about midway between the upper and lower ends thereof, said vertical flue being provided with dampers above and below said points of communication, a horizontal flue extending longitudinally of the kiln and in communication with the lower end of the vertical flue, and transverse distributing-flues connected with said horizontal flue and in communication with the interior of the kiln through the openings in the floor thereof.

4. The combination, substantially as set forth, with a brick-kiln, of a vertical flue opening at its upper end into the kiln near the top thereof and extending below the bottom thereof, an elevated fire-box in communication with said flue at a point about midway between the upper and lower ends thereof, said vertical flue being provided with dampers above and below said points of communication, a horizontal flue extending longitudinally of the kiln and in communication with the lower end of the vertical flue, transverse distributing-flues connected with said horizontal flue and in communication with the interior of the kiln through the openings in the floor thereof, vertical descending flues, also opening near the top of the kiln, and a horizontal exit-flue below said longitudinal distributing-flue for connecting said descending flue with the smoke-stack.

5. A brick-kiln having a floor which is solid near the side walls and perforated in its central portion, said kiln being provided with main flues connected with said perforated floor, and with auxiliary perforations in its

sides near the floor for the admission of heat to the bricks on the solid portions of the floor, substantially as described.

6. The combination, substantially as set forth, of a brick-kiln having a floor which is perforated in its central portion and solid at its side portions, a series of transverse flues or channels beneath said floor, and longitudinal distributing-flues at the sides of the kiln below said transverse flues, provided with top openings into said transverse flues, and flues connecting said longitudinal distributing-flues with the fire-boxes.

7. The combination, substantially as set forth, with a brick-kiln having a perforated floor, of the elevated fire-boxes 6, the vertical flues 12, provided with dampers 13 and 14, with fire-holes 11, and with openings 16 at their lower ends, the longitudinal distributing-flues or fire-chambers 17, the transverse distributing-flues 18 immediately below the perforated

floor, the descending flues 21, provided with dampers, the horizontal exit-flues 23, provided with dampers, and the horizontal central exit-flue, 24, provided with a damper. 25

8. The combination, substantially as set forth, of a kiln, the elevated fire-boxes 6 at the sides thereof, the vertical flues 12, provided with fire-holes 11 about midway between their upper and lower ends, with the dampers 13 and 14 above and below said fire-holes, and with the perforations 15 between said fire-holes and the lower dampers, 14, the partially-solid and partially-perforated floor 19, the transverse flues 18 beneath said floor and in communication with said flues 12, and the central exit-flue, 24, in communication with said transverse flues. 30 35
